HEIGHT-ADJUSTABLE TABLE

John J. Keal, Los Angeles, Calif., assignor to
Brown-Saltman, South Gate, Calif., a corpora-
tion of California

Application December 22, 1952, Serial No. 22,810

Term of patent 14 years

(Cl. D33—14)

To all whom it may concern:

Be it known that I, John J. Keal, a citizen of the United States, residing in Los Angeles, in the county of Los Angeles and State of California, have invented a new, original, and ornamental Design for a Height-Adjustable Table, of which the following is a specification, reference being had to the accompanying drawing, forming part thereof.

Fig. 1 is a perspective view of a height-adjustable table showing my new design.

Fig. 2 is a side elevational view thereof to a larger scale with a small portion of the table top broken away.

Fig. 3 is a sectional view of the table base as taken on line 3—3 of Fig. 2, and shown on a reduced scale.

Fig. 4 is a side elevational view, to the scale of Fig. 3, taken at forty-five degrees to Fig. 2, and with the table top lowered from the position of Fig. 2.

I claim:

The ornamental design for a height-adjustable table, substantially as shown.

JOHN J. KEAL.
